(57) **CLAIM**

The ornamental design for a dental instrument as shown and described.

DESCRIPTION

The patent or application file contains at least one drawing executed in color. Copies of this patent or patent application publication with color drawing(s) will be provided by the Office upon request and payment of the necessary fee.

1.1 is a front perspective view of a dental instrument showing my new design;

1.2 is a bottom view thereof;

1.3 is a left side view thereof;

1.4 is a right side thereof;

1.5 is a front view thereof;

1.6 is a rear view thereof; and

1.7 is a top view thereof.

2.1 is a front perspective view of a dental instrument showing my new design;

2.2 is a front view thereof;

2.3 is a rear view thereof;

2.4 is a bottom view thereof;

2.5 is a left side view thereof;

2.6 is a right side view thereof; and

2.7 is a top view thereof.

3.1 is a front perspective view of a dental instrument showing my new design;

3.2 is a bottom view thereof;

3.3 is a top view thereof;

3.4 is a front view thereof;

3.5 is a left side thereof;

3.6 is a right side thereof; and

3.7 is a rear view thereof.

(Continued)

4.1 is a front perspective view of a dental instrument showing my new design;
 4.2 is a rear view thereof;
 4.3 is a bottom view thereof;
 4.4 is a top view thereof;
 4.5 is a left side thereof;
 4.6 is a right side thereof; and
 4.7 is a front view thereof.
 9.1 is a front perspective view of a dental instrument showing my new design;
 9.2 is a bottom view thereof;
 9.3 is a rear view thereof;
 9.4 is a front view thereof;
 9.5 is a top view thereof;
 9.6 is a right side thereof; and
 9.7 is a left side view thereof.
 10.1 is a front perspective view of a dental instrument showing my new design;
 10.2 is a bottom view thereof;
 10.3 is a right side thereof;
 10.4 is a rear view thereof;
 10.5 is a front view thereof;
 10.6 is a left side view thereof; and
 10.7 is a top view thereof.
